HARRY LAWSON, OF NEW YORK, N. Y., ASSIGNOR OF ONE-HALF TO FRED W. KUEHNAST,
OF MOUNT VERNON, NEW YORK.

UMBRELLA SAFETY DEVICE.

1,326,068.

Specification of Letters Patent. Patented Dec. 23, 1919.

Application filed April 30, 1919. Serial No. 293,731.

To all whom it may concern:

Be it known that I, HARRY LAWSON, a citizen of the United States, and a resident of the city of New York, borough of the Bronx, in the county of Bronx and State of New York, have invented a new and Improved Umbrella Safety Device, of which the following is a full, clear, and exact description.

10 This invention relates generally to a safety device for umbrellas and more specifically to a stop member adapted to be positioned upon the main rod or staff of the umbrella to prevent the umbrella from being turned inside-out when used in high winds.

One of the objects of this invention is to provide a safety stop adapted to be positioned upon the upper portion of the umbrella stem.

20 Another object of this invention is to provide a stop adapted to be positioned on the main umbrella rod or staff to limit the movement of the sliding collar carrying the bracing ribs, and to further function 25 as a stop or support with which the bracing ribs may directly contact, thus acting as a direct support therefor, so that the increased strain thrown upon these bracing members will be taken from the ends of the 30 bracing ribs where they are wired or seated within the sliding collar.

A further object is to provide a detachable safety stop for an umbrella which is readily adapted to be applied to umbrellas 35 already in use, the stop being so constructed as to occupy but little space when the umbrella is closed, but yet furnishing ample bearing space upon the umbrella rod and having a projecting shoulder which will 40 effectively serve to act as a direct stop for the bracing ribs, thus relieving the strain from the ends of said ribs, as above noted.

A further object of this invention is to provide a stop which is simple in construction 45 and inexpensive to make and which is readily adapted to be applied to any umbrella.

While heretofore there has been provided a stop for the sliding collar, which carries 50 the ends of the bracing ribs which, in the usual construction, are retained in the sliding collar by a wire connection, such a stop has been found to be ineffective to prevent the turning of the umbrella inside-out. It

has been found that invariably when an umbrella has turned inside-out in heavy winds, the ribs have given way at the point of connection, so therefore, in the present invention there is provided a stop member positioned on the umbrella staff or stem 55 between the sliding collar and the end of the umbrella, there being provided for said stop a projecting shoulder which will furnish a direct support for the bracing rods between the ends thereof, thus relieving the 60 extra strain and tension at the ends of the 65 said bracing members carried in the sliding collar.

In the accompanying drawings showing one preferred form of the invention similar 70 characters of reference designate like parts in the several views.

Figure 1 is a view of an umbrella shown in raised position with the stop positioned 75 therein.

Fig. 2 is a broken elevation view partly in section showing more clearly the position and character of the stop.

Fig. 3 is a sectional plan view taken on the line 3—3 of Fig. 2.

Fig. 4 is a broken elevation view partly in section showing a modified form of stop member having a raised bead around the edge of the projecting shoulder of the stop.

In the accompanying drawings showing 85 one of the preferred forms of the invention, the stop member is shown as comprising two parts 1, 2, connected together by screws 3 or other suitable means, there being an opening extending through the center thereof so 90 that the parts may be positioned upon an umbrella staff or stem 4 which may be of the ordinary type.

One part 1 of the stop comprises a semi-circular annular member 5 having a shoulder 95 6 at one end and extending therearound, the other part 2 comprising another semi-circular annular ring formed to fit with the first portion and form a continuation of the shoulder 6, the inner semi-circular annular portion being cut away to form a flat surface to receive the heads of the screws.

A stop member is shown in Fig. 2 as being positioned on the stem 4 between the usual spring catch 7 and the usual collar 8 in 105 which is carried one end of the umbrella ribs 9. The usual sliding collar 10 is provided, in which is secured the ends of brac-

ing ribs 11 of the umbrella. The ends 11 of the bracing rods are usually secured to the collar 10 by passing a wire 12 around the collar and through openings in the ends 5 of the bracing rods 11.

It is understood that there is no claim here made to the particular construction of the umbrella, the construction of the parts above enumerated being well known 10 in the art.

One of the important features in the construction of the stop is that the shoulder 6 should extend a sufficient distance from the stem 4 so that when the umbrella is 15 raised, in which position the collar 10 will rest upon the spring catch 7, the outer edge 13 of the said shoulder 6 will contact with the bracing ribs 11 between the ends thereof, as at a point inward from the point of 20 support 12, and will act as a rest or support for said bracing ribs 11. Thus it is seen that the main strain is relieved from the ends of the bracing ribs at the point of connection 12 with the sliding collar 10 and 25 is taken up by the shoulder 6 of the stop.

A modified form of the stop is shown in Fig. 4 in which a bead or ridge 14 is formed at the edge and on the under side of the shoulder 6. The position of the parts are 30 shown in the positions which they would occupy when heavy winds are blowing. The stop 5 is shown in this view as being spaced a greater distance from the spring catch 7 than that shown in the other figures. 35 When the stop is so positioned, the sliding collar 10 under normal weather conditions will rest upon the spring catch 7 and the bracing ribs 11 will be out of engagement with the edge of the shoulder 6 of the stop, 40 but, when heavy winds prevail, there will be a tendency for the ribs 9 to spread outward, thus carrying the sliding collar 10 toward the end of the staff 4, thus bringing 45 the ribs 11 in contact with the shoulder 6 of the stop.

The stop is preferably made of metal or other suitable material.

It is understood that certain changes and modifications of the preferred form herein shown may be made without departing from the spirit and scope of this invention, the improved feature being the provision of a stop adapted to be positioned on the umbrella staff to function as a stop or support for the bracing ribs. 55

Having thus described the invention, what I claim as new is:

1. In an umbrella, comprising a staff, a collar sliding thereon and bracing ribs connected with said collar, a rigid stop detachably mounted on the staff at the upper end to act as a stop having a projecting portion positioned to contact with the bracing ribs between the point of connection with the sliding collar and outer end. 60 65

2. In an umbrella, the combination of a staff, a sliding collar therefor, bracing ribs connected thereto, a spring catch for said collar and a stop member positioned on said staff between the end of the staff and the 70 spring catch to contact with the bracing ribs between the ends thereof to act as a stop to limit the movement of the bracing ribs.

3. As an article of manufacture, a stop adapted to be rigidly positioned on the staff 75 of an umbrella at one end thereof, the said umbrella having a sliding collar and bracing ribs connected to said collar, the said stop having a shoulder which comes in direct contact with and acts as a support for 80 the bracing ribs intermediate their ends.

4. As an article of manufacture, a stop member adapted to be rigidly positioned on the staff of an umbrella to come in direct contact with the bracing members thereof, 85 the said stop comprising a plurality of parts each having a shoulder portion for bracing the ribs, and a means for securing said parts upon the staff in fixed relation.

HARRY LAWSON.
